RING TWISTER

Edouard Roatta, Argues-la-Bataille, and Albert Peysonneaux, Grenoble, France, assignors to Comptoir des Textiles Artificiels, Paris, France, a corporation of France

Application May 27, 1947, Serial No. 750,739
In France July 16, 1946

1 Claim. (Cl. 57—121)

1

This invention relates to continuous twisting frames. More particularly, it relates to a new and improved ring for ring twisting frames.

Copending application for "Ring twister," Serial No. 750,738, filed May 27, 1947, discloses a ring twister wherein the ring on which the traveller slides is rigidly secured in spaced relationship, as by a boss, to a cylindrical shield which, in use, is centered about and disposed in spaced relationship to the bobbin on which the thread is wound. By such construction, the staining of the yarn, both during the twisting-winding operation and when the thread broke, was substantially and materially reduced. In the preferred embodiment disclosed in said application, there is also disclosed a traveller of a certain construction which is disposed in a vertical position on the outside of the ring.

An object of this invention is to provide a new and improved ring twister.

Another object of this invention is to provide a ring twister wherein the height of the ring can be adjusted relative to the height of the shield.

Other and additional objects will become apparent hereinafter.

The objects of the invention are accomplished, in general, by adjustably mounting the ring on and in spaced relationship to a cylindrical shield which is adapted to be centered about and disposed in spaced relationship with respect to the bobbin on which the thread is wound. In the preferred embodiment of the invention, the traveller is of the type usually employed in the cotton industry and is slidably disposed horizontally of the ring.

The invention will become clear from the following description when considered in connection with the accompanying drawings forming a part of this specification, and wherein:

Figure 1 is a side elevation, partly in section, of one position of a ring twisting frame embodying the principles of the invention; and

Figure 2 is a fragmentary section of a modified form of the ring twister.

Referring now to the drawings wherein like reference numerals designate like parts, the reference numeral 1 designates a spindle provided with a pulley 2 which is driven in the known manner (not shown) and on which a bobbin 3, on which the twisted thread is wound, is secured in the known manner.

As is disclosed in the drawings, a ring 4 is secured to the top of a ring carrier 5. On the top of the ring 4, a traveller 6 is disposed horizontally. The traveller 6 is of the type usually em-

ployed in the cotton industry and is formed by bending a metal wire into substantially C-shape.

The ring carrier 5 is adjustably secured to the bottom flange 8 of a cylindrical shield 7 which is adapted to be centered about and disposed in spaced relationship to the bobbin 3. The shield together with the elements carried thereby are reciprocated axially of the bobbin in the known manner.

As is shown in the drawings, the shield 7 is disposed in spaced relationship to the ring 4 and carrier 5 whereby an annular chamber 10 is formed therebetween. The chamber 10 can contain lubricating oil, and the ring 4 can be lubricated in any known manner, for example by capillary action through the provision of appropriate holes necessary therefor.

In the form shown in Figure 1, the height of the ring is adjusted by means of spacers 9 which are appropriately secured between the bottom of the ring carrier 5 and the flange 8. In practice, the spacers 9 are adjusted so that the top edge of the ring 4 will be slightly higher than the top edge of the shield 7, whereby the thread 15 A passing from beneath the traveller 6 will clear the top edge of the shield 7 and pass radially onto the bobbin.

Instead of the adjusting means shown in Figure 1, the ring carrier 5', as shown in Figure 2, can be tapped on its inner periphery and adjustably secured on a threaded collar 8' formed integrally at the bottom of the shield 7'. Thus, upon relative rotation between the shield 7' and the ring carrier 5', the relative heights of the ring 35 4 and shield 7' can be adjusted.

Since various means for adjusting the relative heights of the ring 4 and shield 7 will be apparent to a person skilled in the art, the invention is not restricted to the specific form hereinbefore described.

The invention provides a ring for a ring twister whereby not only is the staining of the thread prevented both during operation and when the thread breaks, but also the ring can be used upon appropriate adjustment with different sizes of thread and yarn.

Since it is obvious that various changes and modifications can be made in the above description without departing from the nature or spirit thereof, this invention is not restricted thereto except as set forth in the appended claim.

We claim:

In a ring twister, a cylindrical shield adapted to be centered about and disposed in spaced relationship to a bobbin on which the twisted

thread is wound, a ring disposed in spaced relationship to said shield and carrying a traveller feeding thread to said bobbin, said shield being provided with an outwardly extending flange, and a ring carrier carrying said ring and threaded onto said flange for vertical adjustment with respect to said shield.

EDOUARD ROATTA.
